RESPIRATOR MASK AND HEADGEAR COMBINATION OR THE LIKE

Guy G. Klinger, Wernersville, and William G. Sockel,
Reading, Pa., assignors to The Electric Storage Battery
Company, Philadelphia, Pa.

Filed Dec. 23, 1958, Ser. No. 53,873

Term of patent 14 years

(Cl. D83—1)

Fig. 1 is a side elevational view of a respirator mask and headgear combination or the like embodying our new design, the opposite side not shown being substantially like the side shown;

Fig. 2 is a rear elevational view thereof, the broken-line representation of a mask being omitted for convenience of illustration; and

Fig. 3 is a top perspective view thereof.

The dominant features of our design reside in the full-line portions of the drawing.

We claim:

The ornamental design for a respirator mask and headgear combination or the like, substantially as shown and described.
